HENRY W. HARPER, OF BERLINSVILLE, PENNSYLVANIA.

Letters Patent No. 95,342, dated September 28, 1869; antedated March 29, 1869.

IMPROVED MACHINE FOR GRINDING AND POLISHING SLATE.

The Schedule referred to in these Letters Patent and making part of the same.

To all whom it may concern:

Be it known that I, HENRY W. HARPER, of Berlinsville, Northampton county, Pennsylvania, have invented an Improved Slate-Grinding and Polishing Machine; and I do hereby declare the following to be a full, clear, and exact description of the same.

My invention relates to mechanism, fully described hereafter, for grinding and polishing school-slates; and it consists—

First, of a screw, so arranged as to regulate the extent to which the slates have to be reduced.

Second, in the combination of a pointer and graduated plate with the said screw, for the purpose of guiding the attendant in operating the same.

In order to enable others familiar with machinery of this class, to make and use my invention, I will now proceed to describe its construction and operation, reference being had to the accompanying drawing, which forms a part of this specification, and in which—

Figure 1 is a vertical section of my improved slate-grinding and polishing machine, and

Figure 2, a transverse vertical section on the line 1-2, fig. 1.

The frame of the machine consists, in the present instance, of the base A, the four posts B B B B, and the cross-bars C C and D.

E and F are two vertical shafts, turning below in steps a on the base A, and above, in suitable bearings b on the cross-bar D.

To the shaft E is secured a disk or wheel, G, having an annular recess, d, and a central projecting hub, e.

The disk is surrounded by a metal ring, f, between which and the split ring h in the annular recess d, are confined the slates i, by means of bolts j, both of the rings f and h projecting a short distance above the upper surface of the disk, but not so far as to reach the upper surface of the slate.

A yoke, H, (fig. 1,) is secured to the opposite beams, C C, of the frame, and through this yoke passes a screw, m, provided with a handle, n, the forked short arm of a lever, I, (hung to a projection on the yoke,) being adapted to a groove formed at the upper end of the screw, and the long arm serving as a pointer for the graduated plate J on the yoke.

To the upper end of the shaft F is secured a disk, K, to the under side of which is attached a ring, L, composed of vulcanized rubber or gutta-percha, combined with pulverized quartz or emery, the material of which the well-known vulcanite emery-wheels are composed, being especially applicable to the purpose.

The ring should be of such a diameter that its periphery will project a short distance beyond the inner end of the slates on the disk G, as shown in fig. 1.

The shaft E is permitted to have a limited vertical movement in its bearings, and is controlled by a lever,

M, connected to a standard, q, on the base A, the forked portion of the lever passing between collars t t on the shaft.

After loosening the nuts of the bolts j, and thereby permitting the split ring h to contract, the slates i are placed on the disk G, and the nuts are then tightened, so as to expand the ring, and thus confine the slates between it and the outer ring f.

The revolving shaft E, with its disk G, is then elevated, so as to cause the slates to bear against the under surface of the rotating grinding-ring, which rapidly reduces them to the desired level surface.

It is important that the upward movement of the shaft E should be limited, so as to prevent too great a reduction of the slates, and prevent the rings f and h from coming in contact with the grinding-surface.

The height to which the slates have to be elevated, and the extent to which they have to be reduced, may be regulated with precision, by turning the screw m, the coinciding of the pointer with certain predetermined marks on the graduated scale, guiding the operator in adjusting the screw.

I have found that a rapidly-revolving emery-ring, L, has a much better effect in reducing or polishing the slates on the revolving disk G, than a plain grinding-disk, the surface of the slates being more uniform and free from scratches than when a disk is used.

Although I prefer to turn the disk G and the grinding-ring L in contrary directions, the two may turn in the same direction, the grinding-ring revolving rapidly, and the disk for holding the slates turning at a lower rate of speed.

The grinding-ring L may be secured to arms radiating from a central hub on the shaft F, instead of to the disk K.

It will be evident that more than one disk for holding the slates, and any desired number of grinding or polishing-rings may be applied to one frame.

Without confining myself to any particular arrangement or construction of frame-work, or to any specific arrangement of gearing or belts for driving the disks or rings,

I claim as my invention, and desire to secure by Letters Patent—

1. The screw m, arranged on the machine substantially as described, for regulating the extent of the reduction of the slates.

2. The combination of the said screw with a pointer and graduated plate, for the purpose specified.

In testimony whereof, I have signed my name to this specification, in the presence of two subscribing witnesses.

H. WM. HARPER.
